[57] CLAIM

The ornamental design for a control panel, as shown
and described.

DESCRIPTION

FIG. 1 is a front perspective view;
FIG. 2 is a rear perspective view;
FIG. 3 is a front elevation;
FIG. 4 is a right side elevation;
FIG. 5 is an underside elevation;
FIG. 6 is a left side elevation;
FIG. 7 is a top elevation; and,
FIG. 8 is a bottom elevation.

The structure shown in broken lines is not a part of the
design but indicates the environmental structure on
which the control panel may be mounted. The characteris-
tic feature of the design resides in the aesthetic
arrangement of the modules.
